(57) **CLAIM**

The ornamental design for a battery lamp, as shown and described.

DESCRIPTION

The claimed battery lamp is used for giving light. It was designed to comprise two halves of different patterns and shapes fixed together. Each half could be rotated to turn on or off the light. When one half is rotated 180 degrees, it could change from the shape of a fish to the shape of a bird or vice versa. It could be worn around the neck as an ornament.

FIG. 1 is a front elevational view of a battery lamp showing my new design, with the wire at the end shown broken away to indicate indeterminate length;

FIG. 2 is a front elevational view thereof, with the side portion shown in an alternate position;

FIG. 3 is a front elevational view thereof, with the side portion in another alternate position;

FIG. 4 is rear elevational view thereof;

FIG. 5 is a right side elevational view thereof;

FIG. 6 is a left side elevational view thereof;

FIG. 7 is a front elevational view thereof; and,

FIG. 8 is a rear elevational view thereof.
